(57) **CLAIM**

The ornamental design for an array microphone assembly, as shown and described.

DESCRIPTION

FIG. 1 is a front, top, right perspective view of an array microphone assembly, showing the new design; FIG. 2 is a rear, bottom, left perspective thereof; FIG. 3 is a top plan view thereof; FIG. 4 is a bottom plan view thereof; FIG. 5 is a front view thereof; and, FIG. 6 is a left side view thereof.

The broken lines of even length shown in the drawings illustrate portions of the array microphone assembly that form no part of the claimed design.
